UNITED STATES PATENT OFFICE.

CHARLES E. DURYEA, OF PHILADELPHIA, PENNSYLVANIA.

TRACTOR.

Application filed December 19, 1917. Serial No. 207,952.

My invention relates to that class of self-moving vehicles more particularly adapted to towing and propelling farming implements, although serviceable for other uses, 5 and the improvements herein described have as their objects, among others, the lowering of cost, lessening of weight, increasing of traction and facilitating operation in a number of ways which will appear in the more 10 complete description.

Other objects and advantages of the invention will hereinafter appear and the novel features thereof will be more particularly pointed out in the appended claims.

15 The invention, in its preferred forms, is clearly illustrated in the accompanying drawings, forming a part hereof.

Similar letters refer to similar parts throughout the several views, of which

20 Figure 1 is a plan of a light construction.

Figure 2 is a longitudinal section of the same on the line 2—2 of Figure 1.

Figure 3 is a detail of the common form 25 of steering mechanism, taken on the line 3—3 of Figure 2.

Figure 4 is a cross sectional elevation, on the line 4—4 of Figure 1, of the bearing and levers by which the driving rollers are forced into engagement.

30 Figure 5 is a sectional plan of the countershaft of Fig. 2, with parts broken away.

Figure 6 is a perspective view, in detail, of the operating lever.

Figures 7 and 8 are details, in plan and 35 cross section respectively, the latter on the line 8—8 of Figure 5, of the speed changing device.

Figure 9 is a side elevation of the steering pedal.

40 Figure 10 is a plan view of Figure 9, more complete.

Figure 11 is a plan of a heavy construction embodying power means of forcing the driving rollers into engagement, the details 45 of the device being shown at Figures 12 to 16 inclusive, of which

Figure 12 is an enlarged substantially central section through the hand valve block, parallel to line 14—14 of Figure 13.

50 Figure 13 is a section on the line 13—13 of Figure 12.

Figure 14 is a section on the line 14—14 of Figure 13.

55 Figure 15 is a sectional detail at right angles to Figure 13.

Figure 16 is an enlarged longitudinal sec-

tion through the cylinder of the power control mechanism.

Figure 17 is a detail in top plan of a hitch 60 for tandem trailers.

Figure 18 is an enlarged view of the draw-bar with parts in section and portions broken away, also seen in Figure 2.

Figure 19 is a detail elevation of a modified form of hitch.

Figure 20 is a skeleton plan.

Figure 21 is a side elevation.

The main frame *a* carries a dead axle *a'* on which the wheels *c c* are journaled. It also serves as a mounting for the safety 70

wheel *a''* carried at the front as a guard against upsetting forward when changing from one implement to another. This frame also carries a steering segment *a''*, Figures

1, 2 and 3, in which a worm *a''* engages at 75 the will of the operator, but which may be disengaged by depressing the eccentric pedal *a''*, Figures 1, 2, 3, 9 and 10. The frame *a*

supports the driving shaft *b* journaled in sliding bearings *b' b''* and driven by sprocket 80

b'' and chain *b''* from the smaller sprocket *b''* on the engine shaft *b''*, and also supports the engine with its tanks and fittings which are not shown because not involved in the invention described herein. It is evident that

any suitable power plant may be used, but more commonly an internal combustion engine using liquid or gaseous fuel is well fitted.

The driving wheels are proportioned in 90 size to the work to be done and, as shown in Figures 1 and 2, may have pneumatic tires adapted for hauling road vehicles or light

implements not requiring great tractive ability, or, as shown in Figure 11, may be fitted 95 with metal tires *c' c''* and cross cleats or

grousers for use in heavy duty, as in plowing, but, in any event, they are fitted with driven rings *b'' b''* forming multiple V-surfaces adapted to be engaged by complementary

100 grooves in rollers *b'' b''*, said rings being of two diameters with the rollers located between them so that moving the rollers lengthwise the vehicle engages one ring or the other and, correspondingly, produces

in that wheel a forward or reverse movement. The construction of these rings and

rollers is more particularly shown in United States Patent No. 1,034,769 of August 6, 1912, and so need not be more fully de-

scribed here.

It will be obvious that since the inner ring

is smaller than the outer one, the roller engaging it should be proportional if the forward and reverse movements are to be approximately the same. Considerable variation in this matter is of little moment, however. While usually tractor speeds are very low with a great speed reduction from the engine speed and, therefore, have little use for additional reduction, I make use of the two sizes of rollers to secure an emergency speed for extremely slow and difficult service and I do this by making the shaft b in three sections splined or squared together to turn as one, but permitting endwise lengthening or shortening, as shown in Figures 5 and 8, in which the outer section b^{11} slides into the central section b^6 , being manually moved by the shifter collar b^{16} with handle b^7 and held by springs b^8 b^9 in retaining notches b^{18} b^{19} in the tubular shell which, being fixed on the central portion b^6 , carries the bearing b^{10} which allows sliding only since there is no rotation at this point except that of the complete shaft b in the bearing blocks b' b' which have inner bearing surfaces of the shape of a sphere section and outer surfaces permitting them to slide more or less radially with respect to the driving wheels c c and by this means I can readily predetermine which collar shall engage with the group of ridges. A degree of variation from a radial position is not objectionable, but offers some advantages in that there is some tendency of the rollers to roll into tighter contact with consequent less non-driving controlling pressure required to engage them and also less tightening and loosening of the chain as the shaft is moved fore and aft. These bearings are mounted to move at an angle from the wheel radius less than would cause the driving action of the rollers to move them into harder contact, that is to say, the reaction of the driving effort tends to thrust the bearing in a direction opposite to the driven wheel movement, but care should be taken to insure that the angle is not such as would result in a greater wedging effect than will permit of self release when the normal engaging pressure is removed. Since the location of the engine does not always permit this bearing shifting to be along a chord of an arc having its center at the center of the engine shaft and since chains usually stretch and need some adjustment, an idler s is shown on the slack side of the chain, as shown in Figure 2, to keep it from becoming loose enough to jump off the sprockets and this idler allows any needful variation in the distances between the sprocket centers. Thus it will be seen that the spheric bearing surfaces, the sliding bearings, and the chain with idler permit moving the shaft b fore and aft, or one end fore while the other is moved aft, or one end may be moved at will while the

other remains practically stationary. Since but little power is needed in turning, it does not matter that the rollers do not engage squarely or that the chain is slightly twisted. Other methods of securing equivalent movements may be used, one of which is shown in United States Patent No. 1,208,111 issued December 12, 1916, but which is not so simple to construct nor so cheap as the improvement herein described. 75

For the lighter work for which slight roller pressures suffice, manual pressure is applied to the sliding bearings b' b' by a link d , lever d' with its pivot d^2 and extension d^3 actuated by rods d^4 d^4 from the vertical lever d^5 to which motion is imparted by the operator through the hand rod d^6 . This rod d^6 passes through a swivel e' at the top of the post e , which swivel carries a pawl e^2 engaging notches d^{21} along the under side of the hand rod d^6 . Ball and socket, or equivalent, joints, are used whenever needed to permit proper operation as follows. The operator pushes the hand rod d^6 forward to send the shaft b forward for forward pulling and locks it into engagement as tightly as needed by the pawl e^2 . He releases this engagement by twisting the rod d^6 until the teeth d^{21} are no longer in engagement with the pawl e^2 , when he may pull the rod b^6 rearward and apply the reverse. If he wishes to make a short turn, as at the end of a plow furrow, he pushes the end of the hand rod d^6 to one side as if he were attempting to push the vehicle around in the desired direction, which push throws the vertical lever to the opposite side and, in effect, pushes one rod d^4 and pulls its mate, thus applying forward motion to one driving wheel and reverse motion to the other. If at the same time he applies fore or aft pressure, he will cause one wheel to drive forward or backward, as desired, before the rollers and rings engage on the other. Since these actions are used only in turning, and for short radii at that, the operation takes but a small amount of time, and since little or no forward progress takes place, very little muscular effort is needed, on which account no provision for locking the parts in a selected position need be provided. It will be apparent that during the turning operations just described, the more common form of steering, consisting of the worm a^4 with its set of bevel gears and usual steering column and wheel, must either move with the main frame a or be disengaged therefrom. Thus, if a light garden implement like a walking plow is used, the weight of the shaft b and other parts on the front of the main frame largely balance the weight of the implement and render it easy to lift it out of the ground while turning. The operator then holds the implement free of the ground with one hand while backing 100 105 110 115 120 125 130

one wheel or sending the other forward, to make the short right angle turn needed in plowing or any other maneuver desired and can assist turning by exerting the implement-holding hand in the required direction. In such handling the steering mechanism remains engaged and ready for use to correct the direction by the steering wheel movement when the rollers are in use and drawing the plow forward. But, if the implement is of the riding type having wheels and frame of its own and, therefore, not liftable but such that it requires turning on its own wheels, the common form of steering mechanism is temporarily disengaged by depressing the pedal a^5 and releasing the rack a^3 and main frame a from the steering mechanism, which is mounted on the draw bar f and to which draw bar f the implement is attached by its tongue, or beam, or some such equivalent. When thus detached, the implement can be turned as perfectly by manipulating the tractor as it could with a team. Further consideration of the draw bar construction will be given later.

Having described the simpler hand-operated form of direction control, the action of the power control used in the heavier and more common form of tractor, now to be described, will be more readily understood. In this the piston rod g , Figure 16, takes the place of the rod d^4 ; the cylinder g^2 is carried on the main frame a and two flexible tubes g^3 g^4 connect each cylinder with the hand valve block g^5 in which the valves g^r and g^1 with the by-pass valve g^p are located. In addition to the four cylinder pipes, two from each, an inlet pipe i and an outlet pipe o also join the valve block g^5 . The outlet pipe o runs to a tank (not shown) in any suitable location, from which tank a pump operated by the engine forces liquid into the valve block g^5 through the inlet pipe i . The liquid enters a distributing chamber j , Figures 12 and 15, from which it may flow into the ends of the valves g^r and g^1 , if they are set to pass it, or else it will force open the by-pass valve g^p against the forked spring l and return to the tank via the outlet pipe o . The amount of pressure on this liquid is that of the spring l acting on the valve g^p and is adjustable by turning the knob k' which is screwed onto the squared stem k of the valve. If all power is desired off, the operator pulls the knob k' until its large cylindric portion k^4 is drawn between the two prongs of the spring l , in which position it will remain until power is again wanted, while the liquid from the pump simply passes to the outlet pipe without resistance or doing work on the pistons. Air cushions y y are fitted to the cylinders to allow a slight movement to follow ring inequalities.

When the valve handles of the valves g^r and g^1 are horizontal, the liquid pressure cannot reach the pipes g^3 g^4 and so the pistons do not act, but, on the contrary, both pipes connect with the outlet by means of the valve construction shown in Figures 12 and 13, on which account the piston allows the roller to freely move away from the ring and take a non-active position. The pipes g^3 g^4 , being flexible, permit the valve block g^5 being carried on the draw bar and moving therewith, whereas the lighter rod and lever construction had to be mounted on the main frame a and move with it. This is not objectionable in the smaller sizes, since the operator can usually reach the hand rod handle even if the wheels are turning in a small circle, but in the larger sizes the same angle would require a longer and inconvenient reach.

The draw bar f may serve as a draw bar and as a support to maintain the implement and tractor in an upright position, or simply as a steering device for the implement and a support for the tractor. Since many implements now drawn by tractors were formerly horse-drawn, they usually are not designed to be drawn by the tongue, but must have a chain or cable to hitch to their draw clevis just as their design calls for. Every one who knows how beautifully a well-balanced plow will stand upright and maintain an even depth without being held, will understand that any attempt to draw such a plow by any other hitch would at once cause trouble and greatly increased draft. I, therefore, make the draw bar adjustable as to length and swivel it to allow the tractor and the wheeled implement to follow the ground surface with their own wheels and provide means for making it rigid when needed, as well as means to allow it to yield in length when towing the implement by the chain hitch. This construction is shown in Figure 18 where the rear end of the draw bar is drawn to a larger scale than the remainder and in which f' is the rear portion of the draw bar. This passes through a tubular part of the front portion and has holes f^{10} in which pins f^2 f^2 may be placed to adjust the length. Springs f^3 f^3 may be used at one or both ends of the tubular portion or omitted, leaving ample space for telescoping. A groove f^4 is shown at the top of the rear portion in which one or more set screws f^5 may project. If not set down fully, they allow the bar parts to telescope, but not to swivel. If partly withdrawn, they permit free motion; if fully set down, they render the two parts of the bar rigid as one.

Not only is a chain or cable hitch needed, but it must be at the standard height to properly pull certain implements like the walking plow mentioned heretofore, and,

therefore, I provide near the center of the axle a' an adjustable attaching post or point m , for the said chain or cable n . Not only does this vertically adjustable post insure proper draft to the implement, but if this draft is taken by the tractor at any point below the axle it tends to lift the rear of the frame which, being resisted by the draw bar and tongue of the implement, results in 10 downward thrust of the driving wheels and, consequently, improved traction, just as the increased angle of pull helps to hold the tractor to the ground if the cable runs to the axle or above, but without introducing 15 traction difficulties at the implement by towing it at a wrong height or depending on the rigidity of the draw bar to transmit much tractive force. While the adjustable post m may be strong enough to take the whole 20 pull of the implement, it will usually be found advisable to attach the cable to the main frame forward of this post m and use the post for adjustment only, forcing the cable down to the desired line.

25 Since implements differ in length, I make the steering and control columns and rods or the flexible tubes in such manner as to permit adjusting the steering wheel and the control a greater or less distance from the axle to bring them within reach of the operator. I show in Figure 2 a vertical adjustment for the steering column, but such adjustment and the support for the valve block on the housing of the steering column 30 (not shown) are so common as to need no illustration.

35 The steering column v^2 , carrying the steering wheel v' and arranged within the sleeve v , carries the bevel gear v^3 meshing with the bevel gear v^4 on a shaft mounted in the tubular T v^5 , as seen in Figures 2, 3 and 10. The shaft a^{41} , with its eccentric a^{42} in the sleeve a^{45} having the stud a^{44} , is shown clearly in Figures 3, 9 and 10.

40 v^6 , through which the draw bar f passes, has a hook member v^7 which supports the rack a^8 , as seen in Figures 2 and 3.

45 The foregoing description being largely diagrammatic, I reserve the right to construct my mechanism with such mechanical modifications as may be necessary to carry out the functions and ideas involved herein in a workmanlike and workable manner, and to meet the needs of the farmer or other owner who may possess one or more of these vehicles. For instance, I may carry the valve blocks and hand wheel to a position further front on one of the tractors and then by joining the draw bars, as at f^{20} to 50 form a rigid reach, I provide a chassis suitable for carrying a large body and having all four wheels capable of being used for propulsion. Thus arranged, either pair of wheels may be steered separately or both 55 together; and any selected wheel may be

driven or all of them. It will be understood that for such use I release the sprocket instead of the worm. With such a construction usually but one power plant will be used, but for very heavy service the second 70 power plant becomes instantly available by engaging the rollers while the wheel is moving which will turn over and start the second engine.

75 The frame a is shown of such proportion that the length is greater than the width, but can well be shorter and have the steering segment a^3 continued to form a much larger arc and permit a much more complete turn when steered to the limit. Or the same 80 result could be obtained by carrying the segment a^3 out to a point near the tires, as shown in Figure 1.

85 While these tractors will be used for such jobs as are within their range, they can be combined by an owner having two and form a four-wheeled chassis on which a suitable body may be mounted. This combination is easily effected in the following manner. The 90 steering column v , Figure 2, may be set vertical if the segment which supports the same is so made as to permit this. The upper end of the columns v may be removed and a sprocket fitted to the vertical stubs of the columns v remaining. Two tractors thus fitted may have their draw-bars f joined, as indicated in Figure 17, which union brings one steering segment ahead of its axle center and the other behind its axle center. These sprockets shown at t^3 and t^4 on the 95 shafts t^5 and t^6 , Figure 17, may both be operated by a single chain t^2 which is propelled by the small sprocket t^1 carried by a steering column t located at any suitable place on the body fitted to the chassis, or, if the body is removable the steering column t may be carried by a bracket from the forward draw-bar f . The contact of the chain t^2 with the sprockets t^3 t^4 should be such that both 100 segments are moved to the same side of the line of the draw-bars f and thus cause the front pair of wheels to turn in one direction while the rear pair turn in the other and closely follow in the curved tracks of the forward ones.

105 By the use of a jaw clutch, not shown, one

110 of the sprockets may be released from its steering column and the worm a^4 will hold its segment in fixed relation to the draw-bar f , while the other sprocket steers its segment 115 and pair of wheels. By the use of such clutch and suitable operating means for it, the steering may be done by one pair of wheels only or by both; while if both sprockets are thus supplied, the operator 120 may choose which pair of wheels he will use for steering and thus secure perfect steering whether the vehicle runs forward or backward. Naturally, the flexible tubes and 125 valve blocks for applying the power and 130

any controls for operating the throttle and spark may be carried to the top of the column ⁵ or in some similar position where the operator can operate them and one engine only may be used to drive one or two wheels or both engines may be used, and all four wheels driven. The second engine will not require starting since meshing it with the wheels of the moving vehicle will set it in motion. This double power plant thus becomes most perfect for use in difficult places since it may be steered in any direction and any two wheels may be driven. It is also economic since but one engine need be used if the other is not needed.

No brakes are shown, but it is evident that shoe brakes, as described in the earlier patent mentioned above, may be fitted or that the pump pressure may be diverted to a cylinder and piston and caused to apply brakes, very readily.

Other modifications in details, proportions of parts etc. may be resorted to without departing from the spirit of the invention or sacrificing any of its advantages.

What is claimed as new is:—

1. In a motor vehicle, an engine shaft, a countershaft mounted in bearings which permit of moving it bodily fore and aft in the vehicle, and also to permit moving either end fore and aft independent of the other, a flexible connection between said engine and countershaft, grooved rollers on the countershaft ends, vehicle wheels with complementary ridges to engage said rollers, means for predetermining the roller which shall engage and means manually operated for causing a predetermined roller to engage predetermined ridges.

2. In a motor vehicle, an engine shaft, a countershaft mounted in bearings which permit of moving it bodily fore and aft in the vehicle, and also permit moving either end fore and aft independent of the other, a flexible connection between said engine and countershaft, grooved rollers on the countershaft ends, vehicle wheels with complementary ridges to engage said rollers, and power means manually controlled for causing a predetermined roller to engage predetermined ridges.

3. In a motor vehicle, an engine shaft, a countershaft mounted in bearings which permit of moving it bodily fore and aft in the vehicle, and also permit moving either end fore and aft independent of the other, a flexible connection between said engine and countershaft, grooved rollers on the countershaft ends, vehicle wheels with complementary ridges to engage said rollers, and manually adjustable power pressure manually controlled means for causing a predetermined roller to engage predetermined ridges.

4. In a motor vehicle, a countershaft

mounted and driven to permit limited fore and aft movement, grooved friction rollers on its ends, driving wheels with complementary friction ridges, bearings for said shaft to permit such fore and aft movement as well as any angularity resulting therefrom, and power means manually adjustable and controlled for moving said shaft in a predetermined manner, said power means comprising a pressure pump driven by the engine and two double acting pressure cylinders having their pistons connected to said bearings and connected with said pump and a regulating valve and a plurality of controlling valves in such connection.

5. In a motor vehicle, a countershaft mounted and driven to permit limited fore and aft motion, grooved friction rollers on its ends, complementary friction ridges on the vehicle driving wheels, bearings to permit such fore and aft motion and any angularity resulting therefrom, and means for moving said shaft to engage said rollers and ridges, said bearings being mounted to move at an angle from the wheel radius less than would cause the driving action of the rollers to move them into harder contact.

6. In combination in a two wheel garden tractor, means for driving either wheel in forward or reverse direction, power driving means therefor, a single mechanically operated controlling means laterally movable to effect driving connection on one wheel in one direction and to release drive on the other wheel, or effect drive in reverse direction, said means being so arranged that the force applied in effecting control of power is also effective to assist in turning the vehicle.

7. In a motor vehicle, a countershaft mounted and driven to permit limited fore and aft movement, grooved friction rollers on its ends, driving wheels with complementary friction ridges, bearings for said shaft to permit such fore and aft movement as well as any angularity, and power means manually adjustable and controlled for moving said shaft in the aforementioned predetermined manner, said power means comprising a pressure pump driven by the engine and two double acting pressure cylinders having their pistons connected to said bearings and connected with said pump and a regulating valve and a plurality of controlling valves in such connection.

8. Driven wheels carrying rings, a drive shaft carrying complementary rollers to engage said rings, mountings for said shaft to permit either end to move fore and aft, means for driving said shaft and permitting said movement, and means for applying at will said rollers to said rings or any one of them.

9. In a motor vehicle, a shaft mounted and driven to permit limited fore and aft motion, grooved friction rollers on its ends,

complementary friction ridges on the vehicle driving wheels, bearings to permit such fore and aft motion and any angularity, and means for moving said shaft to engage said 5 rollers and ridges, said bearings being mounted to move at an angle from the wheel radius less than would cause the driving action of the rollers to move them into harder contact.

10. 10. In a motor vehicle, means for propelling either of a pair of driving wheels in a forward or reverse direction at will, control means for effecting such forward and reverse drives, a single member for actuating 15 such control means, a support for said member, said member being reciprocable on and rotatable in said support to effect operation of said control means, and means operative between said member and support to 20 hold the member with variable pressure against reciprocation.

11. In a motor vehicle-friction-driven mechanism on one of the wheels thereof,

friction-drive mechanism for cooperation therewith, means for moving them into operative limiting wedging contact, and means including angularly disposed drive-shaft bearings at such an angle with respect to a line drawn radially from the centre of the vehicle wheel as to cause the reaction of the 30 friction driven mechanism to automatically assist the driving contact.

12. In a motor vehicle, means for propelling either of a pair of driving wheels in a forward or reverse direction at will, control means for effecting such forward and reverse drives, a single member for actuating 35 said control means, a support for said member including a post and a part swiveled thereto, said member being reciprocable on and rotatable in said support to effect operation of said control means, and means operative between said member and swivel to hold the member against reciprocation.

In testimony whereof I affix my signature.
CHARLES E. DURYEA.
